NECKTIE CLASP

George A. Ingleby, Cranston, R. I., assignor to
 The Hadley Company, Incorporated, Providence, R. I., a corporation of Rhode Island

Application June 7, 1950, Serial No. 166,600

8 Claims. (Cl. 24—49)

1

The principal objects of this invention are to provide a necktie holder which, while maintaining the free portions of a tie in proper position on a garment with maximum protection against inadvertent or accidental displacement and without danger of distortion or damage to the tie, will facilitate insertion of the free portions of the tie into the holder, and will afford adjustability of the holder to conform to varying widths of neckties.

Further objects of the invention are to provide a necktie holder which is simple and compact in structure, pleasing and ornamental in appearance, easy to operate and economical to manufacture.

In one aspect the invention involves a tie holder comprising a backing member having at least at one of its ends a slide mounted for movement to contracted and extended positions lengthwise of the backing member, means for holding the backing member on the garment, and a pair of arms each overlying the backing member in spaced relation thereto, one arm being connected at its outer end to the outer end of the slide and the other arm being connected at its outer end to the opposite end of the backing member, at least one of said arms being hingedly connected for swinging movement from closed position away from the backing member to open position when the slide is in extended position, the inner ends of the arms telescoping together when the slide is moved to contracted position while the hinged arm is in said closed position. One arm may be hingedly connected at its outer end to the outer end of the slide and the other arm may be hingedly connected at its outer end to the opposite end of the backing member. The backing member may have a slide at each of its opposite ends, each slide having an arm overlying the backing member and connected at its outer end to the outer end of the slide, at least one of the arms being hingedly connected to the slide, the inner ends of the arms telescoping together when the slides are moved to contracted position while the hinged arm is in closed position.

In a preferred aspect each slide has an arm hingedly connected at its outer end to the outer end of the slide.

In a more specific aspect, one arm has parts disposed on both sides of the other arm when the same are telescoped together thereby to interlock the arms against movement to open position.

For the purpose of illustration a typical embodiment of the invention is shown in the accompanying drawings in which

2

Fig. 1 is a front elevation showing the tie holder in operative position in association with a tie and shirt;

Fig. 2 is a front elevation of the tie holder in fully closed position;

Fig. 3 is a top plan view of the embodiment of Fig. 2;

Fig. 4 is a section along the lines 4—4 of Fig. 2;

Fig. 5 is a section similar to Fig. 4 with the slides in extended position;

Fig. 6 is a top plan view of the embodiment of Fig. 2 with the slides in extended position and the arms in open position;

Fig. 7 is a front elevation partly in section corresponding to Fig. 6; and

Fig. 8 is a rear elevation of the embodiment of Fig. 2.

Referring to the drawings the numeral 1 designates in general an elongate backing member comprising a channel, the base of the channel being depressed adjacent one end 2 so as to define a housing 3 for accommodating through an opening provided in the side wall 4 of the housing the end of a resilient clasp member 5. The clasp member 5 is here shown by way of example as a piece of looped wire embracing the rear face of the channel base and bent into the form best shown in Figs. 3 and 7, the converging ends of the wire being flattened and received into the housing 3 and there fixedly secured by suitable means as solder.

Mounted at opposite ends 2 and 6 of the channel for slidable movement lengthwise thereof from contracted to extended positions are elongate slides indicated generally by the numerals 7 and 8, each comprising a front resilient member 9 and a rear resilient member 10. Said resilient members are fastened together intermediate their ends by suitable means here shown as a U-shaped member 11 having a reduced end portion 12 extending through slots 13 provided in said resilient members, the tip 14 of the reduced end portion being peened over to engage the rear face of the rear resilient member 10 adjacent its slot and the shoulders defined by the reduced end portion engaging the front face of front resilient member 9 adjacent its slot.

Each rear resilient member 10 is provided adjacent its inner end 15 with a struck-up resilient tongue 16 extending longitudinally toward the opposite end of the member and normally urged rearwardly. The ends of the tongues 16 are operative when the slides 7 and 8 are moved to extended positions to engage the outer walls of

apertures 17 formed adjacent opposite ends of the base of the channel thereby to constitute stops for limiting the extended positions of the slides. The base of the channel is further formed equidistant its opposite ends with a transverse raised rib 18 operative when the slides 7 and 8 are moved to contracted positions to cooperate with the inner ends of the rear resilient members 10 to constitute a stop limiting the contracted positions of the slides. The resilient front and rear members 9 and 10 are reduced adjacent there outer ends 20, the front resilient members 9 being formed with spaced rearwardly directed ears 21 straddling the end portions of the rear resilient members 10 and each provided with an aperture 22.

At the outer end of slide 8 a substantially U-shaped arm support 23 has one leg 24 disposed between the end portions of resilient front and rear members 9 and 10 and is provided with projecting lugs 25 pivotally received in apertures 22 of ears 21 as best shown in Figs. 4 and 5. The base 26 of the U thence extends about the end of the front resilient member 9 while the other leg 27 of the U thence extends over the front face of the front resilient member 9 in spaced relation thereto.

Mounted on the front face of leg 27 and extending longitudinally of and in spaced relation to the slide 8 and backing member is an arm 28 having one end extending outwardly slightly beyond the junction of the leg 27 and base 26 of the arm support 23 and conforming substantially to the curve thereof and its opposite end terminating at a point approximately aligned with the transverse rib 18 of the channel when the slide 8 is in fully extended position as shown in Fig. 5. In this manner the arm 28 is hingedly connected through the arm support 23 to slide 8 and can be swung from a closed position shown in Fig. 5 to an open position shown in Fig. 6. Because the resiliency of the end portions of front and rear resilient members 9 and 10 exert a force normally urging the same together, this force acts upon the inner end of leg 24 and the point of junction between the leg 24 and base 26 disposed therebetween as shown in Figs. 4 and 5 normally to maintain the arm 28 in closed position. As the arm is swung to open position the inner end of base 26 acts as a cam to force the outer end portions of the resilient members 9 and 10 further apart thereby further to oppose said force with the result that upon returning the arm from the open position shown in Fig. 6 the arm will be urged to the closed position with a snap action. Moreover, when the arm is in fully open position the said force of the front resilient member exerted on the inner leg 24 together with the force of the rear resilient member exerted on the outer face of the base 26 will retain the arm in open position until returning movement of the arm is started.

At the outer end of slide 7 an arm 30 is provided at one end with similar projecting lugs 25 pivotally received in apertures 22 of ears 21. Adjacent said end the arm is formed with a leg portion 31 and a base portion 32 similar to the leg 24 and base 26 of arm support 23. The leg portion 31 is similarly disposed between the end portions of front and rear resilient members 9 and 10 and the base portion 22 similarly extends forwardly about the end of the front resilient member 9. At the forward end of the base portion 32 the arm is bent at substantially right angles and extends outwardly along a line drawn 75

along the longitudinal axis of the slide 7 and thence is bent back parallel thereto to form an extension loop 33. Thence the arm extends longitudinally of and in spaced relation to the slide 7 and backing member terminating at a point approximately aligned with the transverse rib 18 of the channel and opposed to the inner end of arm 28 when the slide 7 is in extended position as shown in Fig. 5. In this manner the arm 30 is hingedly connected to slide 7 and can be swung from a closed position shown in Fig. 5 to an open position shown in Fig. 6, said similar parts operating in the same way as above described in connection with arm support 23 normally to maintain arm 30 in closed position, to urge the arm from open position to closed position with a snap action and to retain the arm in open position until the returning movement is started. From the foregoing it is apparent that arm 30 or arm 28 with its arm support 23 may be hingedly mounted at the outer end of either slide 7 or 8 and further that both arms may be hingedly mounted on both slides either in the manner of arm 30 or arm 28.

Adjacent its inner end, the arm 28 is provided with suitable means for telescopically receiving the inner end portion of arm 30 thereby to interlock the arms against swinging movement to open position, said means here being shown, by way of example, as longitudinally spaced rigid loops 34 and 35 simulating the loop and buckle of a belt, the legs of which loops straddle the arm 30 and are fast to the sides thereof. To further enhance the particular ornamentation here disclosed the inner end portion of arm 30 is provided with longitudinally spaced openings 36 and the extreme inner end 37 is reduced respectively to simulate the holes and end of a belt. It is of course contemplated that other suitable interlocking means may be employed for this purpose including, though not by way of limitation, the provision of an arm 28 of tubular construction into which the inner end portion of arm 30 may be similarly telescopically received.

While it is to be noted that the loop extension formed in arm 30 is provided in the typical embodiment shown and described to accurately center the buckle ornamentation midway between the edges of the free end portions of the tie when the slides 7 and 8 are in normally fully contracted position, it is understood that the same result may be obtained without such loop extension by shortening the arm 28 and lengthening the arm 30 an amount equal to the length of said extension or by lengthening slide 7 an equal amount.

In use the slides 7 and 8 are moved to their fully extended position and the arms 28 and 30 are swung open to the fully open position as shown in Fig. 6. The tie holder is then attached to the shirt behind the free end portions of the tie by inserting the hem of the shirt between the clasp member 5 and the base of the channel at which time the hem is firmly clasped and maintained in position therebetween. The free end portions of the tie are then placed between the forwardly projecting arms 28 and 30 after which said arms are returned to the closed position shown in Fig. 5. The slides 7 and 8 are then moved inwardly to the fully contracted position shown in Figs. 2 to 4 during which step the inner end portion of arm 30 is telescopically received within the loops 34 and 35 thereby to interlock the arms against swinging movement to open position. The tie is now held within

the confines of the arms and lightly embraced between the rear faces of the arms and the forward faces of the U-shaped members 11. If at this time the free end portions of the tie do not lie flat because the width thereof is greater than the length of the space within which they are confined, each slide may be extended thereby to increase the space to the required length to accommodate the free end portions of the tie in the desired flat condition. When it is desired to release the free end portions of the tie from the holder the user need only pull the slides to extended position thereby withdrawing the inner end portion of arm 30 from the loops 34 and 35 after which the arms are swung to open position and the free end portions of the tie removed through the opening thus provided.

It should be understood that the present disclosure is for the purpose of illustration only and that this invention includes all modifications and equivalents which fall within the scope of the appended claims.

I claim:

1. A tie holder comprising a backing member having at least at one of its ends a slide mounted for movement to contracted and extended positions lengthwise of the backing member, means for holding the backing member on the garment, and a pair of arms each overlying the backing member in spaced relation thereto, one arm being connected at its outer end to the other end of the slide and the other arm being connected at its outer end to the opposite end of the backing member, at least one of said arms being hingedly connected for swinging movement from closed position away from the backing member to open position when the slide is in extended position, the inner ends of the arms telescoping together when the slide is moved to contracted position while the hinged arm is in said closed position.

2. A tie holder comprising a backing member having at least at one of its ends a slide mounted for movement to contracted and extended positions lengthwise of the backing member, means for holding the backing member on the garment, and a pair of arms each overlying the backing member in spaced relation thereto, one arm being hingedly connected at its outer end to the outer end of the slide and the other arm being hingedly connected at its outer end to the opposite end of the backing member for swinging movement from closed position away from the backing member to open position when the slide is in extended position, the inner ends of the arms telescoping together when the slide is moved to contracted position while the arms are in said closed position.

3. A tie clasp comprising a backing member having a slide at each of its opposite ends mounted for movement to contracted and extended positions lengthwise of the backing member, means for holding the backing member on a garment, each slide having an arm overlying the backing member in spaced relation thereto and connected at its outer end to the outer end of the slide, at least one of the arms being hingedly connected to the slide for swinging movement from closed position away from the backing member to open position when the slides are in extended position, the inner ends of the arms telescoping together when the slides are moved to contracted position while the hinged arm is in said closed position.

4. A tie clasp comprising a backing member

having a slide at each of its opposite ends mounted for movement to contracted and extended positions lengthwise of the backing member, means for holding the backing member on a garment, each slide having an arm overlying the backing member in spaced relation thereto and hingedly connected at its outer end to the outer end of the slide for swinging movement from closed position away from the backing member to open position when the slides are in extended position the inner ends of the arms telescoping together when the slides are moved to contracted position while the hinged arms are in said closed position.

5. A tie holder comprising a backing member having at least at one of its ends a slide mounted for movement to contracted and extended positions lengthwise of the backing member, means for holding the backing member on the garment, and a pair of arms each overlying the backing member in spaced relation thereto, one arm being connected at its outer end to the outer end of the slide and the other arm being connected at its outer end to the opposite end of the backing member, at least one of said arms being hingedly connected for swinging movement from closed position away from the backing member to open position when the slide is in extended position, the inner ends of the arms telescoping together when the slide is moved to contracted position while the hinged arm is in said closed position, one arm having parts disposed on both sides of the other arm when the arms are telescoped together, thereby to interlock the arms against movement to said open position.

6. A tie holder comprising a backing member having at least at one of its ends a slide mounted for movement to contracted and extended positions lengthwise of the backing member, means for holding the backing member on the garment, and a pair of arms each overlying the backing member in spaced relation thereto, one arm being hingedly connected at its outer end to the outer end of the slide and the other arm being hingedly connected at its outer end to the opposite end of the backing member for swinging movement from closed position away from the backing member to open position when the slide is in extended position, the inner ends of the arms telescoping together when the slide is moved to contracted position while the arms are in said closed position, one arm having parts disposed on both sides of the other arm when the arms are telescoped together, thereby to interlock the arms against movement to said open position.

7. A tie clasp comprising a backing member having a slide at each of its opposite ends mounted for movement to contracted and extended positions lengthwise of the backing member, means for holding the backing member on a garment, each slide having an arm overlying the backing member in spaced relation thereto and connected at its outer end to the outer end of the slide, at least one of the arms being hingedly connected to the slide for swinging movement from closed position away from the backing member to an open position when the slides are in extended position, the inner ends of the arms telescoping together when the slides are moved to contracted position while the hinged arm is in said closed position, one arm having parts disposed on both sides of the other arm when the arms are telescoped together,

7
thereby to interlock the arms against movement to said open position.

8. A tie clasp comprising a backing member having a slide at each of its opposite ends mounted for movement to contracted and extended positions lengthwise of the backing member, means for holding the backing member on a garment, each slide having an arm overlying the backing member in spaced relation thereto and hingedly connected at its outer end to the outer end of the slide for swinging movement from closed position away from the

8
backing member to open position when the slides are in extended position the inner ends of the arms telescoping together when the slides are moved to contracted position while the hinged arms are in said closed position, one arm having parts disposed on both sides of the other arm when the arms are telescoped together, thereby to interlock the arms against movement to said open position.

GEORGE A. INGLEBY.
